ORNAMENT FOR CHRISTMAS TREE

Lambert L. Raymond, Minneapolis, Minn.

Application February 23, 1954, Serial No. 412,018

7 Claims. (Cl. 41—10)

This invention relates to an ornament, and particularly to a reflective type of ornament such as would be suitable as a decoration on a Christmas tree. It is desirable to have a suspended movable or oscillatable type of ornament of reflective material having zones of high reflection thereon, with said reflections appearing to move as said ornament moves or oscillates. It is also desirable to have an ornament with a plurality of colored areas thereon.

It is an object therefore of this invention to provide an elongated ornament suitable as a decoration on a Christmas tree having zones of high reflection thereon.

It is another object of this invention to provide an ornament adapted to be movably hung on a Christmas tree having light reflective spots thereon and having zones of high reflection, said zones appearing to move as said ornament is moved or oscillated.

It is a further object of this invention to provide an ornament adapted to be hung on a Christmas tree to be oscillatable comprising a member of rigid colored reflective material of elongated triangular form and formed into trough-shape and having thereon a multiplicity of adjacent reflective spots and having reflective zones thereon, an aperture at the wider end of said member and a thread-like means for hanging said ornament to a portion of a Christmas tree.

It is more specifically an object of this invention to provide an ornament to be hung on a Christmas tree comprising a member of sheet material of elongated substantially triangular form being curved about a longitudinal axis thereof to the form of substantially one-half of a cone or being bent about a longitudinal axis to have sides tapering downwardly substantially to a point, a multiplicity of adjacent light reflecting spots thereon formed by indentations in rows generally inclined to said longitudinal axis of said member, said member having an aperture at its wider end, a thread for hanging said member to a portion of a Christmas tree whereby said member is oscillatable, and zones of high reflection extending substantially longitudinally of said member.

It is also an object of this invention to provide an ornament adapted to be hung on a Christmas tree comprising a member of reflective sheet material of elongated substantially trough-shape form having undulating edge portions, a multiplicity of adjacent indentations thereon forming light reflecting spots, said member tapering downwardly substantially to a point and having its sides at its upper and wider end converging inwardly toward said end, said end having an aperture therein, a thread or thread-like member having one end secured in said aperture for hanging said ornament on a Christmas tree and said member having zones of high reflection, which zones move as said ornament is oscillated.

These and other objects and advantages of the invention will be fully set forth in the following description made in connection with the accompanying drawings in which like reference characters refer to similar parts throughout the several views and in which:

2

Fig. 1 is a view in elevation of a modification of applicant's device;

Fig. 2 is a view in horizontal section taken on line 2—2 of Fig. 1, as indicated by the arrows;

Fig. 3 is a view in elevation of applicant's device;

Fig. 4 is a view in horizontal section taken on line 4—4 of Fig. 3, as indicated by the arrows;

Fig. 5 is a top plan view showing a modification of applicant's device;

Fig. 6 is a view in partial vertical section taken on line 6—6 of Fig. 5, as indicated by the arrows;

Fig. 7 is a partial view in side elevation shown on an enlarged scale; and

Fig. 8 is a partial vertical section taken on line 8—8 of Fig. 7, as indicated by the arrows.

Referring to the drawings, applicant's device is shown comprising a member 10. Said member may be formed of any suitable material, but in the present embodiment is disclosed as being formed from a piece of quite thin but rigid sheet material of elongated substantially triangular form. Said sheet is bent about a longitudinal axis so as to be of trough shape and thus have a convex and a concave side. It is desirable to use a material having a highly reflective surface thereon and preferably a colored reflective surface. Said member 10 is shown as having an undulated outer edge portion 10a. Said member 10 has thereon a multiplicity of adjacent indentations 10b. While said indentations could be of various shapes, they are illustrated as being substantially hexagonal in form with inwardly sloping sides 10b1 and flat central bottom portions 10b2 of each of said indentations providing a plurality of reflective areas. Said indentations may be formed in various alignments but are here shown as being formed in rows generally inclined to the longitudinal axis of said member 10. While said indentations 10b could be impressed from either side of member 10, in the embodiment of the invention illustrated, they are impressed from the convex side.

Said member 10 is disclosed as being bent about a longitudinal axis to be of trough shape and to taper downwardly substantially to a point at its lower end. In practice the opposite sides of said member have been of different colors. As shown in Fig. 2, member 10 is shown as comprising a half of a hexagon. Member 10 has zones

10c of high reflection extending from end to end thereof. The sides of said member 10 at its upper end portion have inwardly converging portions 10d with a rectilinear horizontal top portion 10e. Adjacent said upper end portion 10e is an aperture 10f. A thread or thread-like member 11 is provided having one end portion secured in said aperture 10f and its other end will be secured to a support, such as to a portion of a Christmas tree, so as to hold said member 10 in suspension.

In operation, said member 11 will have one end fastened in said aperture 10e at the upper end portion of member 10, and the other end of said member 11 may be suitably secured, as to a portion of a Christmas tree, to hold said member 10 in a suspended position. Said member 10 will be freely oscillatable and may be oscillated by hand or it is adapted to oscillate by any movement of the tree or even by the current of air moving in the atmosphere. Said member 10 will be oscillatable about the longitudinal axis of the plane in which it is disposed. Said indentations form light reflecting spots, each having a plurality of reflective areas. Each of said sides 10b1 and said bottom portions 10b2 of said indentations 10b form light reflective areas. Said sides and bottom portions will respectively reflect light as said member is moved or oscillated or as the light source is moved so that said reflection will move from some of said portions of

55 member 10 will be freely oscillatable and may be oscillated by hand or it is adapted to oscillate by any movement of the tree or even by the current of air moving in the atmosphere. Said member 10 will be oscillatable about the longitudinal axis of the plane in which it is disposed.

60 Said indentations form light reflecting spots, each having a plurality of reflective areas. Each of said sides 10b1 and said bottom portions 10b2 of said indentations 10b form light reflective areas. Said sides and bottom portions will respectively reflect light as said member is moved or oscillated or as the light source is moved so that said reflection will move from some of said portions of

said indentations to other of said portions and said light reflection will extend longitudinally of said rows of indentations. The form of said member 10 provides light reflecting zones 10c extending generally longitudinally of said member and said light reflecting zones will move laterally of said member 10 as said member oscillates or as said light source moves. The high reflective points at the sides of said indentations will change position as said ornament oscillates, thus giving a striking and beautiful effect.

The concave side of said member 10 will have an appearance similar to the convex side thereof, as disclosed in Figs. 1 and 2. Said concave side will also have longitudinal zones of high reflection which will appear to move laterally of said member as said member is moved, oscillated or as the source of light is moved. The high spots on said indentations will also move as above described.

Hence a highly decorative and very pleasing light reflective ornament formed as a pendant is provided.

Referring to Fig. 3, a member 10' is shown which is substantially similar in structure to member 10 having undulated outer edges 10'a, a multiplicity of light reflecting indentations 10'b and an aperture 10'f at its upper end portion. The sides of said member 10' at its upper end portion converge inwardly to form a curvilinear upper end portion 10'e. A thread or threadlike member 11' is shown having one end portion secured in said aperture 10'f and its other end portion will be secured to a suitable support to hold said member 10' in a suspended position. Referring to Fig. 2, said member 10' is disclosed as being curved about a longitudinal axis in the form of a half cone. Said member 10' has zones 10'c of high reflection.

In operation, member 10' functions in the same manner as member 10 in forming a pendant and in having similar light reflecting areas and a similar decorative and pleasing appearance.

With reference to Fig. 5, a modification is shown of a portion of applicant's device. The upper end portion of a member 10'' is shown. Said member 10'' will be similar in structure to said member 10'. The sides of said member 10'' at its upper end have inwardly converging concavely curved portions 10''a. Said upper end portion of member 10'' is bent to lie in a substantially horizontal plane to form a substantially rounded upper end portion having an aperture 10''c therein. Aperture 10''c is substantially coincident with the longitudinal axis about which member 10'' is bent.

In operation, a flexible member similar to member 11 will be provided having one end secured in said aperture 10''c and having its other end secured to a suitable support to hold said member 10'' in suspension as from any desirable portion of a Christmas tree. Said member 10'' is adapted to oscillate about its central longitudinal axis and in all other respects will function as in the operation of member 10' above described.

Thus it is seen that I have provided a simply constructed yet unusually decorative ornament adapted for use on a Christmas tree having a multiplicity of light reflecting spots and having zones of high reflection, which zones move as said ornament is oscillated and thus is provided a very pleasing and beautifully decorative effect. Applicant's device is now being produced on a commercial scale and has proved to be very successful.

It will of course be understood that various changes may be made in the form, details, arrangement and proportions of the parts, without departing from the scope of applicant's invention, which, generally stated, consists in a device capable of carrying out the objects above set forth, in the parts and combinations of parts disclosed and defined in the appended claims.

What is claimed is:

1. A Christmas tree ornament comprising a member of sheet material of general elongated substantially triangular form, the same being formed into elongated

concavo-convex form, said member having rows of small adjacent indentations therein, the inner and outer surfaces of said member being highly reflective whereby each of said indentations constitutes a light reflecting spot and there is a zone of high reflection extending longitudinally of said member at each side thereof.

2. The structure set forth in claim 1, said rows extending longitudinally along said member and being inclined to the longitudinal midline of said member.

3. The structure set forth in claim 1, said member having a top portion extending substantially at right angles to the axis of said member and having a small aperture therein substantially coincident with the central longitudinal axis of said member at its transverse center and a thread of small diameter secured in said aperture and adapted to be attached to a spot for suspending said ornament whereby said member will oscillate about the axis of said thread and said light reflecting spots will appear to move and said zones shift laterally in location.

4. The structure set forth in claim 1, said member having its sides at its upper and wider end converging inwardly and towards said end.

5. A Christmas tree ornament comprising a member of sheet material of general elongated substantially triangular form, the same being bent about a longitudinal line thereof to be of trough shape and forming a portion of a polygon in cross section, said member having rows of small adjacent indentations therein, the inner and outer surfaces of said member being highly reflective whereby each of said indentations forms a light reflecting spot and there is a longitudinally extending zone of high reflection at each side of said member.

6. A Christmas tree ornament comprising a member of sheet material of general elongated substantially triangular form, the same being bent about a central longitudinal axis to be of trough shape and tapering downwardly substantially to a point, said member having undulated edges at its sides, said member having its sides at its upper end portion converging inwardly toward said end, said member having an aperture at its upper end portion, a multiplicity of adjacent indentations in said member forming light reflecting spots and said member having thereon longitudinally extending light reflecting zones, and a thread of small diameter having one end secured in said aperture for hanging said member for oscillation about its central longitudinal axis whereby when said member is oscillated said longitudinal zones of reflection will move laterally of said member.

7. A Christmas tree ornament comprising a member of reflective sheet material of elongated generally triangular form, an undulated edge portion about said member, said member being curved about a longitudinal axis having a wider end portion at its upper end and tapering downwardly substantially to a point, said member having an aperture at its upper end portion, a multiplicity of adjacent indentations forming light reflecting spots formed in said member and formed in rows substantially inclined to the longitudinal axis of said member and said member having light reflecting zones extending substantially longitudinally of said member, and a thread of small diameter having one end secured in said aperture for hanging said ornament in suspension whereby when said member is oscillated said light reflecting spots will appear to move in said rows and said light reflecting zones will move laterally of said member.
